(57) **CLAIM**

The ornamental design for a pair of headphones, as shown and described.

DESCRIPTION

FIG. 1.1 is an isometric view of the pair of headphones in accordance with a first embodiment of the invention.

FIG. 1.2 is a left side view of the pair of headphones in accordance with a first embodiment of the invention.

FIG. 1.3 is a right side view of the pair of headphones in accordance with a first embodiment of the invention.

FIG. 1.4 is a top side view of the pair of headphones in accordance with a first embodiment of the invention.

FIG. 1.5 is a bottom side view of the pair of headphones in accordance with a first embodiment of the invention.

FIG. 1.6 is a front view of the pair of headphones in accordance with a first embodiment of the invention.

FIG. 1.7 is a rear view of the pair of headphones in accordance with a first embodiment of the invention.

FIG. 2.1 is an isometric view of the pair of headphones in accordance with a second embodiment of the invention.

FIG. 2.2 is a left side view of the pair of headphones in accordance with a second embodiment of the invention.

FIG. 2.3 is a right side view of the pair of headphones in accordance with a second embodiment of the invention.

FIG. 2.4 is a top side view of the pair of headphones in accordance with a second embodiment of the invention.

FIG. 2.5 is a bottom side view of the pair of headphones in accordance with a second embodiment of the invention.

FIG. 2.6 is a front view of the pair of headphones in accordance with a second embodiment of the invention; and, FIG. 2.7 is a rear view of the pair of headphones in accordance with a second embodiment of the invention.
